(57) **CLAIM**

The ornamental design for a mounting bracket, as shown and described.

DESCRIPTION

FIG. 1 is a perspective view of a mounting bracket showing frontal and side portions of my new design, with an alternator shown in phantom outline;

FIG. 2 is a side elevational view thereof;

FIG. 3 is a side elevational view of the side opposite from that shown in FIG. 2;

FIG. 4 is a perspective view showing rear and side portions thereof;

FIG. 5 is a front view thereof;

FIG. 6 is a top view thereof; and,

FIG. 7 is a bottom view thereof.

The broken line showing of an alternator in FIG. 1 is for illustrative purposes only and forms no part of the claimed design.
